(57) **CLAIM**

The ornamental design for a belt with buckle, as shown and described.

DESCRIPTION

FIG. 1 is a perspective view of the belt with buckle showing my new design;

FIG. 2 is a front view thereof;

FIG. 3 is a right view thereof;

FIG. 4 is a left view thereof;

FIG. 5 is a rear view thereof;

FIG. 6 is a top view thereof; and,

FIG. 7 is a bottom view thereof.

The dot-dash lines indicate that the belt is of indeterminate length.
